Patented Apr. 20, 1915.

UNITED STATES PATENT OFFICE.

EDWIN S. MAYLAND, OF NEW YORK, N. Y.

MUSICAL DEVICE.

1,136,355.

Specification of Letters Patent. Patented Apr. 20, 1915.

Application filed March 6, 1913. Serial No. 752,294.

To all whom it may concern:

Be it known that I, EDWIN S. MAYLAND, a citizen of the United States, residing at Brooklyn, in the county of Kings, city and State of New York, have invented certain new and useful Improvements in Musical Devices, of which the following is a clear, full, and exact description.

This invention is an improvement in musical devices, and is concerned especially with mechanism for supporting and sounding suspended tubular bells or chimes, the object being to secure an advantageous and space-economizing relation of the parts, to provide an electro-magnetic hammer for striking the bell which is capable of operating efficaciously with a small amount of current, and to secure a unit construction wherein the bell and its associated parts are carried by the magnet frame.

A particular object is to so construct and arrange the hammer and its electro-magnet as to secure great sensitiveness of the hammer by virtue of its mounting and to enable it to execute a long stroke, without a wide initial air gap, thereby deriving the force of the blow largely from momentum with corresponding economy of current.

Another object is to provide the device with a steady bar, advantageously disposed for checking the movement of the suspended tube.

Other features and advantages of the invention will become apparent to those skilled in the art as the specification proceeds.

In the accompanying drawings: Figure 1 is a side elevation of my improved invention for striking a blow on a tubular bell. Fig. 2 is a face view of Fig. 1. Fig. 3 is a partial sectional detail of the striking hammer showing the removable hammer body. Fig. 4 is a back plan view of the supporting bracket.

The tubular bell or chime is designated 13, the same being suspended by means of a cord 12, which passes through apertures in its upper portion. It is operated by means of an electro-magnet 5, arranged to act upon a hammer 3, which I mount in a pendulous manner above and to one side of the tube, the magnet being horizontal and more or less directly over the upper end of the tube.

A magnet frame 1 constitutes the support for all the parts, and preferably consists of a plate or casting having screw-hole ears

7 and 8 whereby it may be applied by means of screws 9 to the face of a primary support 10. Projecting outward from the frame is a trunnion bar or hammer support 2, which is suitably bifurcated at the end to receive the swinging bar of the hammer 3, which is fulcrumed on the support by the pivot points 4. The horizontal magnet 5 is immediately below the bar 2, and between the hammer and the body of the frame, and thus acts upon the hammer close to its fulcrum. In the particular construction shown, the magnet consists of a single core surrounded by a coil, and the hammer support 2 forms part of the magnetic circuit, which is adapted to be closed by the bar of the hammer, forming the armature. The core of the magnet is desirably surrounded by a felt pad 7^a, which prevents the armature sticking to the magnet and thus insures a prompt return of the hammer away from the tube.

The hammer head 28, the relation of which to the tube is such that the latter is struck at the top, is fixed to the end of a flat spring 27, which extends upward along the inner face of the hammer bar 2, and is united thereto by rivets 26, somewhat below the magnet. By this construction the hammer is caused to strike its blow by an over-throw movement, after the rigid hammer or armature bar has been brought to rest against the magnet, and immediately to spring backward, thus avoiding interference with the vibrations of the tube. A felt sleeve 21, held in place by a screw 22, interposes a cushioned or deadened contact surface between the spring 27 and bar 3, and thus avoids any interfering metallic noise. The striking portion is preferably a hard leather piece 30, which projects through an opening in a retaining collar 29.

Normally the hammer stands at an inclination, as shown in Fig. 1, being held yieldingly in this position by suitable means, such as a weight 24 secured to an upward extension 23 of the hammer bar over the hammer support 2, whereon it contacts with a rubber buffer 25 serving as a cushioned abutment. After the forward stroke and the deenergizing of the magnet, the weight restores the hammer to normal position.

On the lower portion of the frame 1 are two projections, preferably carrying hooks 10, forming laterally spaced supports on which the cord 12 is hung. The said lower

portion of the frame also bears a forwardly-projecting arm 14, on the outer end of which is fixed a steady bar 16. The latter extends downward at one side of the hammer and is bent or directed sidewise so that its extremity, bearing a felt pad 17^a, is brought into position to contact with the upper portion of the tube, below and at the same side as the hammer. This device serves to check undue movement of the tube, but does not affect the tone, because the hammer strikes the tube away from the pad. The steady device is of particular value when repeated blows are to be struck, since without it the chime might be set swinging, so as to be struck either when moving away or toward the hammer, thereby causing loss of power or impairment of the sound, or both.

Binding posts 17 and 18 on the lower part of the frame are connected with the ends of the magnet coil, and also receive the ends of wires leading from a suitable source of current, for example batteries 18^a. The circuit is opened and closed and the magnet energized and deenergized by suitable means indicated at 19.

In operation, it will be understood that closing of the circuit energizes the magnet and that the latter draws over the hammer to strike its blow. Because of the construction and arrangement of the parts, the hammer requires very little effort to move it and the stroke obtained is a long one, without however necessitating a wide air gap between the armature and the magnet core, all of these conditions contributing to make it possible to operate the device with but small consumption of current. At the same time the action from the standpoint of the musical effect to be secured is especially suitable. As already explained, the resilient connection of the hammer head with the hammer bar removes the striker immediately from the tube, and as soon as the circuit is opened the hammer swings bodily back to normal position. It will be observed that the flat spring 27 carrying the striker extends for a substantial distance along the inner or forward face of the hammer bar 3, being free to swing forward from the latter but otherwise rigidly sustained thereby. The striker mounted on the projecting end of the spring is close to the end of the bar. In this way a comparatively limber spring can be employed, which will absorb little power at the end of the stroke, and unnecessary vibrations of the striker are avoided.

I claim as my invention:

1. In a musical device, the combination of a magnet frame, a horizontal magnet thereon, a combined armature and hammer fulcrumed on the frame immediately above said magnet and hanging in front of the same, a tubular bell suspended from the frame with its upper portion in position to

be struck by the hammer, and a steady bar projecting downward from the frame and having a cushioned portion in position to contact with the upper part of the bell. 70

2. In a musical device, the combination of a support, a tubular bell suspended therefrom, an electromagnet on the support above the bell, a hammer adapted to be actuated by said magnet depending in position to strike the upper portion of the bell, and a steady bar projecting downward from the support to contact with the upper part of the bell. 75

3. In a musical device, the combination of a suspended tubular bell, a hammer arranged to strike the upper portion of the same, and a steady member having a cushioned portion positioned to contact with the upper part of the bell at the same side as the hammer. 80

4. In a musical device, the combination of a frame, a horizontal electro-magnet thereon, a combined armature and hammer fulcrumed on the frame immediately above said electro-magnet, a tubular bell suspended from the frame, a forwardly projecting arm on the lower portion of the frame, and a steady bar fixed to said arm and projecting downward at one side of said hammer and directed laterally in order to contact with the bell at the same side as and below the hammer. 90

5. In a musical device, the combination with a suspended tubular bell, of a frame above the bell, a hammer depending therefrom in position to strike the upper portion of said bell, an electro-magnet on the frame for actuating said hammer, and a steady bar projecting downward and sidewise from the frame at one side of the hammer with its lower portion in position to contact with the bell below and at the same side as the hammer. 100

6. In a musical device, the combination of a suspended tubular bell, a hammer for striking the same, and a steady member positioned to contact with the upper portion of the bell, the arrangement being such that the hammer blow tends to drive the bell away from the steady member. 110

7. In a musical device, the combination with a bell, of a pivoted hammer bar, a magnet for actuating the same, a flat spring secured to the hammer bar and extending along and free from the forward face of the same for a substantial distance, and a striker fixed to the free end of the spring beyond the end of the bar to strike the bell by overthrow movement. 120

8. In a musical device, the combination with a bell, of a pivoted hammer bar, a magnet for actuating the same, a spring secured to the hammer bar and extending along and free from the forward face of the same for 130

a substantial distance, a striker fixed to the free end of the spring beyond the end of the bar to strike the bell by over-throw movement, and a deadener interposed between 5 the spring and the hammer bar.

9. In a musical device, the combination with a bell, of a pivoted hammer bar, a magnet for actuating the same, a spring secured to the hammer bar and extending along the 10 face of the latter, and a striker fixed to the

end of said spring, said hammer bar extending into proximity to the striker so as to back up the spring.

Signed at New York in the county of New York and State of New York, this 4th 15 day of March, 1913.

EDWIN S. MAYLAND.
